SHOE SEWING MACHINE

Fred Ashworth, Wenham, Mass., assignor to
United Shoe Machinery Corporation, Borough
of Flemington, N. J., a corporation of New
Jersey

Application June 15, 1938, Serial No. 213,786

12 Claims. (Cl. 112—57)

The present invention relates to lockstitch sewing machines which employ a hook needle to draw loops of needle thread through the work, a loop taker, or shuttle, to carry the loop of needle thread over the locking thread and a takeup to pull the loop of needle thread from the shuttle. The invention is herein illustrated as embodied in a shoe sewing machine of the McKay type, an example of which is disclosed 5 in the patent to Bernard T. Leveque No. 1,885,927 issued November 1, 1932, and in the present inventor's Patent No. 1,905,031 issued April 25, 1933. It is to be understood, however, that while the invention is particularly applicable to machines of the type disclosed in the 10 patents referred to certain features of the invention may be used to advantage in other types of hook needle lockstitch machines.

In the machines of the patents referred to the 20 position of the take-up, upon stopping the machine at the end of the sewing operation, is indeterminate and as a consequence, for reasons which will be hereinafter more fully explained, when the machine is again started into operation a varying amount of thread is drawn back into the horn by the take-up before the first 25 stitch is formed and tightened in the work. Also before starting the machine an operator often draws some thread from the horn in order to 30 insure sufficient needle thread for the first stitch. At the beginning of the seam, therefore, a considerable length of thread is often left projecting from the work inside of the shoe, which not only results in a waste of thread but necessitates 35 an appreciable expenditure of time and labor in trimming off this waste end.

The principal object of the present invention is to provide a hook needle lockstitch sewing machine with means for preventing the formation 40 of this waste end of needle thread at the beginning of a seam.

Other objects are in general to improve the construction and operation of hook needle lockstitch sewing machines and more particularly of 45 shoe sewing machines of the type disclosed in the patents above referred to.

With the above objects in view, a feature of the invention consists in the provision in a hook 50 needle lockstitch sewing machine, of a normally open thread lock arranged between the take-up and the work and actuated upon stopping the machine to clamp the thread at a point along the lead of the thread between the take-up and the sewing point and to maintain the thread

in clamped condition after the machine comes to rest.

In order that the operator may, if necessary, draw off an extra length of thread while the machine is at rest, or to enable the machine to 5 be rethreaded in case it becomes necessary to replenish the thread supply, according to another features of the invention, means are provided permitting the operator to release the thread lock after the machine has come to a stop. 10

Other features of the invention consist in certain devices, construction and combinations of parts hereinafter described and claimed, the advantages of which will be apparent to those skilled in the art from the following description 15 taken in conjunction with the accompanying drawings which illustrate an embodiment of the invention.

In the drawings, Fig. 1 is a view in side elevation of a McKay type lockstitch shoe sewing 20 machine embodying the invention; Fig. 2 is a view in left side elevation of the take-up and thread clamping mechanisms of the machine; Fig. 3 is a view in front elevation of the take-up and thread clamping mechanisms shown in 25 Fig. 2; Fig. 4 is a detail view in side elevation of the supplemental thread lock of the invention; Fig. 5 is a detail plan view, partly in section, of the portion of the supplemental thread lock adjacent the thread clamping jaws, taken along 30 the line 5—5 of Fig. 4; Fig. 6 is a detail plan view similar to Fig. 5, but with the movable jaw assembly omitted; Fig. 7 is a diagrammatic view showing the relative positions of the take-up and the thread locks during the sewing operation 35 when the needle loop is passing over the shuttle, the main thread clamp being in closed position, the supplemental lock open, and the take-up 40 commencing its downward stroke; Fig. 8 is a diagrammatic perspective view showing the needle and loop spreader in stopped position with the thread loop supported for severance by the knife; and Fig. 9 is a diagrammatic view showing the parts in stopped position after the thread 45 has been cut and the work removed from the machine, with the thread on the work side of the take-up clamped by the supplemental thread lock, and with the main thread clamp in open position.

Except as hereinafter provided, the machine 50 illustrated in the drawings is of the same construction, arrangement and mode of operation as the machine of Patent No. 1,905,031 above referred to. The machine comprises a column 12 in the lower portion of which is mounted an 55

electric motor 14 by which the operating parts of the machine are driven. The main or sewing cam shaft is indicated at 16 and is journaled in the sewing head mounted on the column. The shaft 16 is driven from the motor 14 through a clutch 18, horizontal shaft 20, gear box 22 and vertical shaft 24. The clutch 18 is controlled by means of a foot treadle 26 by means of which the clutch may be actuated to connect and disconnect the shaft 20 from the motor.

The shoe supporting horn, indicated at 28, is provided in its tip with a whirl of usual construction, which is driven from the vertical shaft 24 through connections comprising a horizontal shaft 30 and a vertical shaft 32 extending upwardly into the base of the horn, the shaft 32 being hollow to provide a passage 34 for the needle thread to the work. An intermediate bevel gear 36 is provided between shafts 30 and 32 as in Patent No. 1,905,031 hereinafter referred to.

The stitch forming devices include the straight hook needle, 38, discoidal shuttle 40, and the loop spreader 42, all actuated from the sewing shaft 16 in the same manner as in the machine of the prior patent. Connections between the sewing shaft and the needle comprise a crank pin on the forward end of the sewing shaft, a slotted lever 44 engaged by the pin, a needle actuating lever 46, a latch 48 connecting the slotted lever and the needle actuating lever, and a link connecting the needle actuating lever to the needle bar 50. The shuttle is driven from the needle actuating lever 46 through a link which is connected to a downward extension from the hub of the lever to an upwardly extending arm of the shuttle actuating gear segment 52. This segment meshes with the pinion 54 mounted upon one end of the shaft which drives the shuttle. The loop spreader is likewise actuated from the needle actuating lever 46 through the connections by which the shuttle is actuated, as described in the aforesaid patent, whereby the loop spreader, during the upward stroke of the needle, is caused to engage and spread one side of the needle loop.

Connections are provided from the starting and stopping treadle 26 for actuating the latch 48 to disconnect the needle actuating lever 46 from the sewing shaft 16 when the needle, shuttle and loop spreader are at the limit of their movements in one direction. The parts are thus brought to rest accurately with the needle loop in the hook of the needle and free of the shuttle and with the supply side of the needle loop engaged and deflected by the loop spreader, the work side of the needle loop being left in position where it can be readily cut by the operator, as illustrated in Figure 8. These connections comprise a rod 56 connecting the treadle with an arm 58 fixed on one end of a cross-shaft 60 mounted in the head of the machine. The arm 58 is provided with a lug 62 projecting laterally beneath a rearward extension of an arm 64 loosely mounted upon the cross-shaft and connected at its forward end by a link 66 to a rock shaft upon the forward end of which is secured an upwardly extending lever 68 by which the needle may be locked in stopped position. A heavy coil spring (not shown) surrounds the cross-shaft 60 and tends to rotate it in a clockwise direction. While the machine is running the treadle 26 is depressed and the lug 62 is held out of engagement with the arm 64. Upon release of the treadle, the clutch 18 is operated to

disconnect the motor from the machine and the arm 58 is swung upwardly, causing the lug 62 to engage the rearward extension of the arm 64. Thereafter, the coil spring, acting through the arm 58, turns the arm 64 in a clockwise direction and through the connection to the lever 68, moves the same in a direction to disengage the latch 48 from the needle actuating lever 46 and to lock the needle at the top of its stroke.

The machine is provided with take-up mechanism similar to that illustrated in Patent No. 1,885,927, said mechanism being actuated from the horizontal shaft 30 by means of a crank pin 70 mounted upon a cam disk 72 secured to the end of the shaft 30. The crank pin 70 is connected by a link 74 to the central pivot 76 of toggle levers 78 and 80, which are connected, respectively, to fixed pivot 82 and to one end of the take-up lever 84 pivotally mounted at the lower end of an adjusting lever 86.

The machine is likewise provided with thread clamping mechanism adapted to be actuated in proper timed relation to the other stitch forming devices. This mechanism, fully illustrated and described in the aforesaid Patent No. 1,885,927, comprises two disks illustrated at 88, loosely mounted on a shaft 90 and interposed between an abutment 92 on the machine frame and the hub of a cam lever 94 secured at one end of the shaft. A cam-faced block 96 is secured to the other end of the shaft, said block being held in engagement with an opposing stationary cam-faced block 98 by means of a spring 100. The cam lever 94 is provided with a cam roll 102 which engages the surface of the cam disk 72 mounted on the shaft 30. When the cam roll rides onto the high portion of the cam disk 72, the shaft 90 is rocked in a clockwise direction and moved to release the thread clamp to permit thread readily to be drawn from the supply. When the cam roll reaches the low portion of the cam disk, the shaft 90 is rocked in a counter-clockwise direction by the action of the spring 100 and the cam blocks 96 and 98 act to clamp the thread positively.

As hereinbefore described, the machine is stopped with the needle at the top of its stroke and before the shuttle has entered the loop of thread supported by the needle and the loop spreader. Due to the fact that the take-up may continue to oscillate for an appreciable interval after the disconnection from the cam shaft of the sewing devices in the head of the machine, means are provided for holding the thread clamp open during the stopping of the machine and until the machine is again started, in order that the thread may not be broken by a downward stroke of the take-up. For this purpose the presser foot lifting mechanism is utilized in a manner fully illustrated and described in Patent No. 1,885,927 above referred to. Briefly, said mechanism comprises a vertically reciprocating lifting lever 104 and a non-reciprocating retaining lever 106 which are caused to engage successively, when cross-shaft 60 is rocked to stop the machine, an arm secured to a rock shaft 108 to which is attached a lever 110 by which the presser foot is raised. The rocking movement of shaft 108 to raise the presser foot is imparted to the shaft 90 of the thread clamping mechanism by connections comprising an arm 112 pivoted on a bolt 114 in the head of the machine, an adjustable set screw 116 in said arm adapted to be engaged by an arm 118 on shaft 108, and a link 120 connecting arm 112 with the

5 rear end of a lever 122 pivotally mounted on a bolt 124 in the machine frame. The forward end of the lever 122 extends beneath a horizontal arm 126 projecting from the hub of cam lever 94 on shaft 90 of the thread clamping mechanism so that when the lever 122 is rocked in a 10 counterclockwise direction, as viewed in Figure 2, the shaft 90 of the thread clamp is rotated in a direction to cause the cam-surface blocks 96 15 and 98 to open the clamp. The opening of the thread clamp by the above described mechanism takes place before the take-up makes its downward stroke in order that the take-up, during such downward stroke, may draw what thread 20 is required through the open clamp from the supply.

25 The presser foot is caused by the retaining lever 106 to remain in raised position while the machine is at rest and until the machine is again 30 started, and the thread clamp is therefore held open by the lever 122. Upon starting the machine, the clutch 18 is engaged and the cross shaft 60 rocked in counterclockwise direction to connect the sewing devices in the head of the 35 machine and to move the retaining and lifting levers 106 and 104 respectively to inoperative position. With the lowering of the presser foot, the lever 122 is permitted to rock in a clockwise direction, thus restoring the actuation of the thread 40 clamp to the cam disc 72.

45 Upon stopping the machine at the completion of a seam, the locking thread and the work side of the needle loop may be readily severed by the operator at a single stroke of the knife, as illustrated in Figure 8. When the threads are so cut, a satisfactory length of needle thread is left 50 above the horn for starting a new seam. In the machine of the prior patents, however, when the shoe is removed from the horn, the friction of the free end of the needle thread in the work may cause thread to be pulled up through the horn. If the take-up has happened to stop at a point above its lower limit of oscillation, thus leaving slack thread between the supply and the work, this slack will be drawn up as the shoe 55 is moved away from the horn. In certain cases the friction of the thread in the work may be sufficient to cause thread to be drawn off from the supply through the open thread clamp, after 60 the slack thread has been pulled up, or where no slack thread was present, the take-up having stopped in its down position. Also an operator sometimes makes a practice of pulling off a length of thread from the supply to insure starting a new seam properly. As a result, a long end of thread is often left projecting from the horn. When the machine is put into operation in starting a new seam, this long end of thread is not 65 wholly drawn back, but a considerable portion 70 is left projecting from the inside of the shoe and must be trimmed, wasting both the thread and the operator's time.

75 In accordance with the present invention, to prevent this result, there is provided in the illustrated machine a supplemental normally-open thread lock arranged to clamp the thread at a point along the lead of the thread between the take-up and the sewing point, which lock is closed upon stopping the machine and is held 80 closed after the machine comes to rest, so as to prevent the withdrawal of thread through the horn from any cause. This supplemental thread lock, best illustrated in Figure 4, comprises a bracket 128 secured at its upper portion by 85 means of machine screws 130 to the machine

frame above and forwardly of the take-up mechanism. The bracket is provided with lugs 132 having recesses formed therein for the reception of cone-pointed screws by which a cover, not shown, for the take-up mechanism may be 90 pivotally secured to the machine frame. The bracket is likewise provided with a pair of laterally spaced downwardly extending arms 134, the lower portions of which extend rearwardly beneath the lower end of vertical shaft 32 of the 95 whirl-driving mechanism. Secured to the lower ends of the arms 134 by means of screws 136 is a U-shaped member 138 comprising the fixed jaw 10 of the supplemental thread lock. In order that the thread may be properly guided to the supplemental thread lock from the take-up, a second U-shaped member 140 (see Figure 6) is secured to the bracket arms 134 at right angles to the fixed jaw 138, the member 140 being provided with a vertically-directed aperture 142 in substantial alignment with the thread passage 34 in shaft 32 and with the clamping surface 144 of the fixed jaw 138.

15 The movable jaw of the supplemental thread lock is indicated at 146, and is yieldingly mounted at the lower end of an arm 148 secured by a taper pin 150 to a horizontal rock shaft 152 journaled in the bracket 128, the arm being arranged to swing between the bracket arms 134 toward and away from the fixed jaw 138. The 20 yielding mounting for the movable jaw 146 comprises a rod 154 slidably received in the arm, the jaw 146 being attached by means of a pin 156 to a lug 158 formed at the inner end of the rod 154. The end of the lug 158 is relieved slightly 25 at its upper and lower corners 160 (see Figure 4) to permit a small amount of rocking movement of the jaw 146 about its pivot 156, whereby the thread may be gripped with uniform pressure 30 throughout the portion engaged by the jaws 35 40 when the lock is applied. The rod 154 is formed adjacent the lug 158 with an enlarged portion 162 which serves as a seat for one end of a compression spring 164 surrounding the rod. The other end of the spring bears against the inner 45 50 face of arm 148. The rod is prevented from slipping out of the arm, when the same is swung away to release the lock, by a collar or head 166 secured to the end of the rod outside the arm 148 by means of a pin 168.

55 To apply the supplemental thread lock upon stopping the machine, the shaft 152 is rocked in a clockwise direction by connections from the lever 122 by which the main thread clamp is opened during the stopping operation. These connections comprise a rearwardly extending arm 170 secured to the rock shaft 152 adjacent the outer end thereof and a downwardly extending member 172 carried by the arm 170 and having a headed portion 174 adapted to bear against the 60 upper side of the forward end of lever 122.

65 To afford, for a purpose to be described, a yield in the actuating connections for the supplemental thread lock, the member 172 is arranged for vertical sliding movement in the arm 170, a relatively stiff compression spring 176 being provided between the under side of the arm and the head portion 174 to transmit the rocking movement from the lever 122 to the arm 170. Check 70 nuts 178 at the upper end of member 172 adjustably limit the downward extension of the member and thereby permit adjustment of the time of application of the supplemental thread lock relative to the opening of the main thread clamp 75.

when the lever 122 is rocked in a counterclockwise direction upon stopping the machine.

To enable the operator to release the supplemental lock while the machine is at rest, in case it becomes necessary for any reason to draw off an extra length of needle thread from the supply, there is provided a handle 180 secured to the outer end of the rock shaft 152. By raising this handle, the arm 148 may be swung outwardly to open the lock, the spring 176 yielding to permit the arm 170 to move relatively to the member 172. Upon release of the handle 180 by the operator, the spring 176 acts upon arm 170 to close the supplemental lock prior to starting the machine. By requiring the operator to perform the additional act of raising the handle 180 before thread may be drawn off manually, waste of thread from this cause is discouraged.

Upon starting the machine, the lever 122 is rocked in clockwise direction, as hereinbefore described, to render operable the main thread clamp, thus simultaneously removing the clamping pressure from the supplemental thread lock. To insure at such times that the thread lock is fully released to remove all resistance to the passage of the thread, a light coil spring 182 surrounds the end of rock shaft 152 and tends to rotate it in counterclockwise direction, as viewed in Fig. 2, one end of the spring engaging the handle 180 while the other end is secured to a lug 184 projecting from the bracket 128.

Having thus indicated the nature and scope of the invention, and a specific embodiment thereof having been described, what is claimed is:

35. 1. A lockstitch sewing machine having, in combination, stitch forming devices including a hook needle, a loop taker and a take-up, a normally open thread lock acting when closed to clamp the needle thread at a point along the lead of the thread between the take-up and the sewing point, and means operating on stopping the machine to close the lock and maintain the lock closed after the machine stops.

45. 2. A lockstitch sewing machine having, in combination, stitch forming devices including a hook needle, a loop taker and a take-up, a normally open thread lock acting when closed to clamp the needle thread at a point along the lead of the thread between the take-up and the sewing point, means for stopping the machine with the take-up in an indeterminate position and with the other stitch forming devices in a position to permit removal of the work and means operating on stopping the machine to close the lock and maintain the lock closed after the machine stops.

55. 3. A lockstitch sewing machine having, in combination, stitch forming devices including a hook needle, a loop taker and a take-up, a normally open thread lock acting when closed to clamp the needle thread at a point along the lead of the thread between the take-up and the sewing point, means operating on stopping the machine to close the lock and maintain the lock closed after the machine stops, and operating on starting the machine to open the lock.

65. 4. A lockstitch sewing machine having, in combination, stitch forming devices including a hook needle, a loop taker, and a take-up, means for stopping the machine with certain of the stitch forming devices in predetermined positions while permitting the take-up to coast to an indeterminate stopping position, and a normally inoperative thread lock rendered operative upon stopping the machine to clamp the needle thread at a point along the lead of the thread between the

take-up and the sewing point and prevent withdrawal of thread from the machine, after the machine stops.

5. In a lockstitch sewing machine having, in combination, stitch forming devices including a needle, a loop taker, and a take-up, mechanism for stopping the machine with certain of the stitch forming devices in predetermined positions while permitting the take-up to coast to an indeterminate stop position, a thread clamp between the take-up and the supply, means for opening and closing said thread clamp during each stitch forming cycle, a normally inoperative thread lock arranged to clamp the needle thread at a point along the lead of the thread between the take-up and the sewing point, and means operating upon stopping the machine to close the thread lock and retain said lock closed after the machine stops and simultaneously to open the thread clamp.

6. A lockstitch sewing machine having, in combination, stitch forming devices including a hook needle, a loop taker and take-up, means operative upon stopping the machine to bring the needle to rest at the top of its stroke with the thread loop over the needle while permitting the take-up to coast to an indeterminate stop position, a normally inoperative thread lock, and means operating upon stopping the machine to actuate said thread lock to grip the thread at a point along the lead of the thread between the take-up and the sewing point and to retain the thread in gripped condition after the machine is stopped.

7. A lockstitch sewing machine having, in combination, stitch forming devices including a hook needle, a loop taker, and a take-up, means operative upon stopping the machine to bring the needle to rest at the top of its stroke with the thread loop over the needle while permitting the take-up to coast to an indeterminate stopping position, a normally inoperative thread lock, and means operating upon stopping the machine to actuate said thread lock to grip the thread at a point along the lead of the thread between the take-up and the sewing point and upon starting the machine to actuate said thread lock to release the thread.

8. A lockstitch sewing machine having, in combination, stitch forming devices including a needle, a loop taker, a take-up, and a thread clamp arranged to act on the thread between the take-up and the supply, means operating on stopping the machine to bring the needle to rest in a predetermined position while permitting the take-up to coast to an indeterminate stop position, normally inoperative means rendered active upon stopping the machine to open the thread clamp and to hold the clamp open until the machine is again started, and a thread lock actuated by said normally inoperative means upon stopping the machine to clamp the thread between the take-up and the work and to retain the thread in clamped condition until the said means again becomes inoperative upon starting the machine.

9. A lockstitch shoe sewing machine having, in combination, stitch forming devices including a needle, a loop taker, a take-up and a thread clamp arranged to act on the thread between the take-up and the supply at predetermined times during each stitch forming cycle, mechanism for stopping the machine with the needle and loop taker, in predetermined positions, the take-up being permitted to coast to an indeterminate stop position.

5 nate stop position, normally inoperative means rendered active upon stopping the machine to hold open the thread clamp until the machine is again started, a supplemental thread lock arranged between the take-up and the work, and connections from said normally - inoperative means for rendering said lock operative only upon stopping the machine and for releasing the lock when the machine is again started, said 10 connections including a yielding member to permit the operator to release the lock while the machine is stopped.

10. A lockstitch sewing machine having, in combination, stitch forming devices including a hook needle, a loop taker and a take-up, a normally open thread lock acting when closed to clamp the needle thread between the take-up and the work, and means operating on stopping the machine to close the lock and maintain the 15 lock closed after the machine stops, said means including a yielding member to permit the operator to open the lock while the machine is stopped.

11. A lockstitch shoe sewing machine having, in combination, a shoe supporting horn adapted to extend inside of a shoe, stitch forming devices including a straight hook needle arranged to pass through the sole of a supported shoe into the horn, a loop taker above the horn to take a loop 20

of thread drawn up by the needle, and a take-up to draw thread back into the horn and pull the loop from the loop taker, a normally inoperative thread lock arranged to act on the needle thread at a point along the lead of the thread between the take-up and the sewing point, and means operating upon stopping the machine to actuate the thread lock to prevent withdrawal 5 of thread from the horn, after the machine stops.

12. A lockstitch shoe sewing machine having, in combination, a shoe supporting horn adapted to extend inside of a shoe, stitch forming devices including a straight hook needle arranged to pass through the sole of a supported shoe into the horn, a loop taker above the horn to take a loop 15 of thread drawn up by the needle, and a take-up to draw thread back into the horn and pull the loop from the loop taker, means for stopping the machine with the needle at the top of its stroke with the thread loop over the needle while permitting the take-up to coast to an indeterminate stop position, a normally inoperative thread lock arranged to act on the needle thread at a point 20 along the lead of the thread between the take-up and the sewing point, and means operating upon stopping the machine to actuate the thread lock to prevent withdrawal of thread from the horn, after the machine stops. 25

FRED ASHWORTH.
